UNITED STATES PATENT OFFICE.

ROBERT C. RICHTER, OF NEW YORK, N. Y.

ROTARY SPARK-GAP.

1,265,959.

Specification of Letters Patent.

Patented May 14, 1918.

Application filed April 13, 1917. Serial No. 161,922.

To all whom it may concern:

Be it known that I, ROBERT C. RICHTER, a citizen of the United States, residing at Rockaway Beach, in the county of Queens, city and State of New York, have invented certain new and useful Improvements in Improved Rotary Spark-Gaps, of which the following is a clear, full, and exact description.

10 This invention relates to the type of spark gap used in radio communication commonly termed rotary spark gaps.

One of the objects of my invention is to provide a rotary spark gap that will produce a radiated current of high frequency, and consequently a high pitched tone in telephone receivers such as are usually employed for the reception of radio signals.

Another object of my invention is to provide means to vary the distance between the electrodes during operation of the rotary spark gap.

Further objects of the invention will appear more fully hereinafter. The invention consists substantially in the construction, combination, location and relative arrangements of parts, all of which will be more fully set forth hereinafter as shown in the accompanying drawings and finally pointed out in the appended claims.

Inasmuch as the electrode carrying disks employed in my invention rotate in opposite directions, the advantages of my invention will be readily apparent to those skilled in the art, a few of which are: the cooling effect upon the electrodes, due to the rotation of the disks opposite to each other, preventing burning of the electrodes and preventing what is commonly termed "arcing" between the same, and also producing a rapid spark quenching effect, greatly to be desired in radio communication, therefore securing increased efficiency; the advantage of having the electrodes on the disks pass each other at twice the rate of speed that they would pass a given point if only one disk was used; the advantage of varying the distance between the electrodes during operation of the rotary spark gap as required,

therefore securing accurate adjustment of the transmitting unit.

Referring to the drawings, in which the same part is designated by the same reference numeral wherever it occurs throughout the several views:

Figure 1 is a plan view of a structure embodying my invention;

Fig. 2 is a side view of the same, partly in section;

Fig. 3 is a rear view of the inner disk, showing a method of connecting the electrodes thereon electrically;

Fig. 4 is a rear view of the structure showing the lever and means whereby the position of the electrodes may be changed.

As shown in the drawings, A is a motor having a hollow shaft 1 supported by suitable collars 3 and 4. Through shaft 1 runs shaft 2, adapted to rotate freely therein, on which shaft 2 are fastened disk 5 and bevel gear 6 at the ends thereof by pins 7 and 8. On shaft 1 are mounted bevel gear 9 and disk 10. The disks 5 and 10 are made of suitable non-conducting composition such as generally used for this purpose. The washer 1^a prevents the disks 5 and 10 from coming closer together, and it will be seen that lever 12 prevents the gears connected to the shafts from changing their distances longitudinally. The electrodes 11 and 11' are made of a suitable conducting metal (preferably zinc) and are mounted in disks 5 and 10. It will be noted that electrodes 11 pass entirely through and project on both sides of disk 5, but that electrodes 11' pass through disk 5, but that electrodes 11' pass through 85 but only project on one side of the disk 10, the purpose of which will be pointed out hereinafter.

I pivotally mount on the shaft 2 a lever 12 which lever 12 comprises a handle, preferably made of non-conducting material, and gear wheel 14 secured thereto by pin 18 and the rocking support 15 and 16. Thus, it will be seen that upon actuation of the lever 12, gear wheel 14 actuates gear 6 and gear 9 in opposite directions to rotate the shafts 1 and 2, and the disks 5 and 10 carried thereby to radially displace or adjust the relative

positions of the electrodes 11, 11' relative to each other. It is desirable to lock the parts in any adjusted position, and for this purpose I provide a wing nut 17 which is adapted to be screwed tight with its associated bolt through the slot indicated in the member 16 and a co-operating slot in the upright wall 18 formed on the base B of the motor A.

Referring again to Fig. 1, gear 9 and disk 10 are fastened to shaft 1 by set screws 19 and 20, or any other desired means. Non-conducting members 21 and 21' are provided with horizontally adjustable conducting rods 22 and 22' passing through them. To make electrical connection with electrodes 11' and disk 10, I provide members 23 and 23' on which are mounted brushes 24 and 24' (made of phosphor bronze, preferably, and of suitable size to permit of the use of heavy current), which brushes contact lightly but firmly on copper member 25 carried by the disk 10 and in electrical connection with the electrodes 11'. The members 23 and 23' are also made of non-conducting material. Screws 26 and 26' are used to tighten the adjustable rods 22 and 22', while screws 27 and 27' are used to fasten brushes 24 and 24' to members 23 and 23'.

Referring to Fig. 3, which shows the back of the disk 10, the copper member 25 is preferably integral and embedded flush with the surface of the disk or otherwise fastened to disk 10. At the end of each radially extending member 25' the electrodes 11' are passed through and then fastened tight in order to make an electrical connection therewith. However, any desired form of connection for this purpose may be used.

The operation of my device is as follows: The motor rotates shaft 1 and bevel gear 9 is thereby caused to rotate, which gear 9 meshes with gear 14, causing said gear 14 to rotate bevel gear 8 in a direction opposite to that of the shaft 1 and gear 9, thereby causing shaft 2 and disk 5 to rotate with gear 8. It will be seen, therefore, that the disks rotate opposite to each other. If the position at which the electrodes pass each other is to be changed, the wing nut 17 is loosened and the lever 12 is moved either to the left or right. It will be apparent that if the lever 12 is swung to the right, its lower part (the bevel gear 14 and support 15, together with slotted member 16) will swing to the left. As the gear 14 swings in the form of an arc, it will be seen that when the gear 14 is moved to the left, for instance one-quarter of an inch, the shaft 1 will advance the disk 5 one-quarter of an inch to the right and the shaft 2 will advance the disk 10 one-quarter of an inch to the left, which operation can be made during the operation of the device, and which changes

the position of the passing of the electrodes 65 in relation to each other and in relation to the stationary electrodes. When the proper space is determined, the wing nut is again tightened and the members 12, 15 and 16 are securely held in position. More or less 70 electrodes may be employed on the disks, and more or less disks may also be used.

I prefer to use motive power of variable speed in order to increase or decrease the frequency, and correspondingly change the 75 tone of the signals.

It will be seen that if the secondary terminals of a step-up transformer, such as used in radio communication, be connected, one with members 22 and 22' and the other 80 with brushes 24 and 24' that the high potential of the current will tend to break down the air gap between electrodes 11' and 11 (the current having traversed through brushes 24 and 24' and copper member 25) 85 and thence from electrodes 11 to conductors 22 and 22', and vice versa, whenever said electrodes are in close enough alinement with each other to permit a spark to jump across the air gaps.

While I have shown and described a specific structure embodying the principles of my invention, I wish it to be understood that my invention in its broad scope as defined by the claims is not to be limited or restricted thereto, as many changes in details of construction will readily appear to those skilled in the art without departing from the contemplated spirit and scope of my invention.

Having now described the objects and nature of my invention, what I claim as new and useful and of my own invention and desire to secure by Letters Patent is:

1. In a rotary spark gap structure, the 105 combination with electrodes, means for rotating said electrodes in opposite directions relative to each other, and means for varying the point in the travel of said electrodes where they pass each other during the rotation of said electrodes.

2. In a rotary spark gap structure, the combination with a plurality of disks carrying electrodes, means for rotating said disks in opposite directions relative to each other, and means for varying the point in the travel of said disks where the electrodes pass each other during the rotation of said electrodes.

3. In a rotary spark gap structure, the 120 combination with a plurality of disks carrying a plurality of electrodes, means for rotating said disks in opposite directions relative to each other, and means for varying the point in the travel of said disks where the electrodes pass each other during the rotation of said electrodes.

4. In a rotary spark gap structure, the

- combination with disks, each carrying an electrode, means for rotating said disks in opposite directions relative to each other, and means for varying the point in the travel of said disks where the electrodes pass each other during the rotation of said electrodes.
5. In a rotary spark gap structure, the combination with disks carrying electrodes, means for rotating said disks in opposite directions relative to each other, said disks being opposed to each other, and means for varying the point in the travel of said disks where the electrodes pass each other during the rotation of said electrodes.
6. In a rotary spark gap structure, the combination with a pair of disks opposed to each other, of a hollow shaft on which one of said disks is carried, a second shaft passing through said hollow shaft and on which the other of said disks is carried, means for simultaneously rotating said shafts in opposite directions, and means for shifting the normal position of said shafts relative to each other.
7. In a rotary spark gap structure, the combination with a pair of disks opposed to each other, of a hollow shaft on which one of said disks is carried, a second shaft passing through said hollow shaft and on which the other of said disks is carried, means for simultaneously rotating said shafts in opposite directions, a lever pivotally mounted on said second shaft, means for rocking said lever relative to said second shaft, and means connecting said lever and both the said shafts for co-incidently moving said shafts relative to each other.
8. In a rotary spark gap structure, the combination with a pair of disks opposed to each other, of a hollow shaft on which one
- of said disks is carried, a second shaft passing through said hollow shaft and on which the other of said disks is carried, means for simultaneously rotating said shafts in opposite directions, a lever pivotally mounted on said second shaft, means for rocking said lever relative to said second shaft, means for connecting said lever and both the said shafts for coincidentally moving said shafts relative to each other.
9. In a rotary spark gap structure, the combination of a source of motive power, a hollow shaft connected therewith, a shaft extending through said hollow shaft and adapted to rotate freely therein, gears mounted on each of said shafts, a gear meshing with both of said first named gears to rotate said shafts in opposite directions, electrode carrying disks on each shaft, means for changing the relative positions of said disks during rotation of the same, and electrodes located in proximity to the disks.
10. In a rotary spark gap structure, the combination of a source of motive power, a hollow shaft connected therewith, a shaft extending through said hollow shaft and adapted to rotate freely therein, gears mounted on each of said shafts, a gear meshing with both of said first named gears to rotate said shafts in opposite directions, electrode carrying disks on each shaft, means for changing the relative positions of said disks during rotation of the same, and electrodes located in proximity to the disks.
- Signed at the city of New York, New York, this 11th day of April one thousand nine hundred and seventeen.
- ROBERT C. RICHTER.
